SOUND REPRODUCING SYSTEM FOR MUSICAL INSTRUMENTS

Ellison S. Purington, Gloucester, Mass., assignor to John Hays Hammond, Jr., Gloucester, Mass.

Application March 4, 1939, Serial No. 259,731

5 Claims. (CL 179—1)

This invention relates to musical instruments having vibrating elements and more particularly to a piano having electrical sound propagating means associated therewith.

5 The invention provides for the use of an auxiliary oscillator, the operation of which is controlled by the variation of the capacity of the pick-up device, which may be made to cause amplitude, frequency or phase modulation of the auxiliary oscillator frequency. Audio frequency tonal currents may be produced by suitable demodulation of the oscillator output.

10 The invention also consists in certain new and original features of construction and combinations of parts hereinafter set forth and claimed.

15 Although the novel features which are believed to be characteristic of this invention will be particularly pointed out in the claims appended hereto, the invention itself, as to its objects and 20 advantages, the mode of its operation and the manner of its organization may be better understood by referring to the following description, taken in connection with the accompanying drawings forming a part thereof, in which;

25 Fig. 1 is a circuit diagram illustrating the general principles used in the customary capacity pick-up arrangement;

Fig. 2 is a schematic diagram of the pick-up and amplifying system as applied to a piano and;

30 Fig. 3 depicts diagrammatically the circuits of a modified form of the invention

Like reference characters denote like parts in the several figures of the drawings.

35 In the following description and in the claims parts will be identified by specific names for convenience, but they are intended to be as generic in their application to similar parts as the art will permit.

40 Referring to the drawings and more particularly to Fig. 1 a plurality of grounded vibratory elements 10 are provided such as the strings of a piano. Located adjacent to the strings 10 is a metallic plate 11 forming with the strings 10 an electrostatic pick-up device. Connected across the strings 10 and the plate 11 is a battery 12 and a resistor 13. The plate 11 is connected through a condenser 15 to the grid of an amplifier tube 16. A resistor 17 is connected across the input circuit of the amplifier 16. The output circuit of the amplifier 16 is connected through a second amplifier 18 and a transformer 19 to a power amplifier 20, the output circuit of which is connected to a loud-speaker 21.

45 50 55 60 65 70 75 80 85 90 95 100 The capacity of the condenser formed between the strings 10 and the plate 11 may be considered to vary in general in accordance with the law $C = C_0(1 + Kf(t))$ in which $f(t)$ is a function of time which varies between the limits —1 and 1, and C_0 and K are constants, which

for example may be $C_0 = 50$ micromicrofarads and $K = .005$.

Assuming simple sine wave vibrations of frequency f cycles per second, $f(t)$, for computational purposes, may simply be $\sin 2\pi ft$. For a range of f in the audio scale, for example from 32 to 4096 cycles per second corresponding to the fundamental tones of the lowest and highest C's on a piano, the voltage across the resistor 17 may be computed for each value of f . The problem may be considered as divided into two parts; first the computation of the voltage e' , which is the A. C. portion of the voltage across the condenser 10—11 assuming resistor 17 to be disconnected and which, disregarding phase, is represented by the formula:

$$e' = \frac{.707 EK}{\sqrt{1 + \frac{2.54 \times 10^{10}}{(RfC)^2}}}$$

in which E is the voltage of the battery 12, assumed to be 200 volts, K is the capacity range factor .005, R is the resistance of the resistor 13, assumed to be 5 megohms f is the frequency in cycles per second and C equals 50 micromicrofarads. e' will be in R. M. S. volts; second the relation

$$\frac{e_g}{e'} = \frac{1}{\sqrt{1 + \frac{m(2+m)}{1+n^2}}}$$

in which e_g is the voltage across resistor 17,

$$m = \frac{R}{R_g}$$

and

$$n = \frac{R}{X_c} = (6.28 \times 10^{-6}) R f C$$

in which R_g is the resistance of the resistor 17 and X_c is the reactance of the condenser 10—11.

The following table gives the computation of the various voltages corresponding to the different frequencies f :

	e'	e_g/e'	e_g	45
32	.0355	.167	.006	
64	.0707	.168	.012	
128	.140	.170	.024	
256	.266	.180	.048	50
512	.441	.213	.093	
1024	.80	.302	.182	
2048	.673	.495	.334	
4096	.695	.735	.51	

These tables indicate the following points: 55

1. For the same values of K for each string the lower notes would be greatly discriminated against, so that the range of capacity variation for the lower strings should be much greater than for the highest strings.

2. The nature of the circuit is inherently such that the harmonic tones are more strongly represented in the electrical output than in the vibrational input.

5 The difficulties encountered with the ordinary type of capacity pick-up as shown in Fig. 1 are as follows:

1. Because of the high impedance of the circuit, and the low pick-up level, it is susceptible to 10 interference from stray electric fields, requiring especially good shielding.

2. Because of the high impedance in combination 15 with high voltage across the pick-up the circuit is susceptible to electrical noise produced by variable leakage across the condenser device.

In order to overcome these undesirable effects the novel types of capacity pick-up circuits shown in Figs. 2 and 3 have been developed. These circuits involve the use of an auxiliary 20 oscillator, the operation of which is controlled by the capacity of the condenser, which may be made to cause amplitude, frequency or phase modulation of the auxiliary frequency, audio frequency tonal currents being produced by suitable demodulation of the oscillator output.

Fig. 2 illustrates the invention as applied to a piano 25, which is provided with the usual strings 26 mounted on a metallic frame 27. Located adjacent to the strings 26 are a plurality of metallic 30 plates 28, which are insulated from the framework of the piano. The frame 27 is connected by a grounded conductor 29 to a fixed adjustable condenser 30 and a variable condenser 31, the other sides of which are connected to one end of a resistor 32. The plates 28 are connected by a conductor 33 to one end of a resistor 35. The other ends of the resistors 32 and 35 are connected together and through a coil 36 to the conductor 29. The coil 36 is inductively coupled to 40 a coil 37 which is the inductor of a tank circuit of an oscillator 38 and supplies A. C. voltage between the junction of the two resistors 32 and 35 and ground. The condenser formed between the strings 26 and the plates 28 and the two 45 condensers 30 and 31 form two arms of a bridge arrangement 34 the other two arms being the resistors 32 and 35.

Connected across the two resistors 32 and 35 is the primary of a transformer 39 the secondary 50 of which is connected in the input circuit of an amplifier 40. The output circuit of the amplifier 40 is connected through a transformer 41 to demodulator and audio amplifier 42. The output circuit of the tube 42 is connected through a 55 transformer 43 to the input circuit of a power amplifier 45 the output circuit of which is connected to a loud-speaker 46. The amplifier 40 and following circuits may be standard circuits of a high grade radio receiver, such for example 60 as the intermediate frequency amplifier and second detector circuits of a superheterodyne. Only so much thereof has been shown as is necessary to an understanding of the present invention.

For automatically controlling the bridge adjustment a D. C. relay 47 may be connected to 65 the variable condenser 31. The relay 47 is operated by a D. C. relay tube 48 which is controlled from the amount of D. C. rectified by the detector 42 as will be described.

70 In the operation of the form of the invention shown in Fig. 2, A. C. voltage is impressed from the oscillator 38 across the bridge arrangement 34 and the condenser 30 is adjusted so that a suitable unbalanced condition results, thus caus-

ing a proper amount of energy to pass through the transformer 39. When the degree of unbalance of the bridge 34 is varied, due to the variation in capacity of the pick-up device 26-28 as the strings 26 vibrate, the energy delivered through the transformer 39 is modulated in accordance with the capacity fluctuations. This modulated energy is amplified by the amplifier 40 and passes through the transformer 41 to the demodulator and audio amplifier 42, the audio frequency output of which corresponding to the 10 string vibrations, passes through the transformer 43 to the power amplifier 45. Here the energy is further amplified and is fed to the loud-speaker 46 where it is reproduced as musical tones.

Some of the D. C. current from the detector 15 device 42 will flow through the resistor 49 in the direction of the arrow causing a potential difference to be built up across this resistor which is proportional to the signal strength. This potential will change the bias on the grid of the relay 20 tube 48 thus controlling the amount of current flowing through the relay which in turn will change the setting of the variable condenser 31. In this way the bridge arrangement 34 is adjusted so as to maintain correct off-balance conditions, 25 as indicated by the detector energy, regardless of any variation in the average capacity of the pick-up device. This control arrangement, however, is not essential to the operation of the system.

This system of amplitude modulation by capacity variations using the bridge method has been shown for purposes of illustration. Other systems of amplitude modulation by capacity variations may be used in its place without changing the scope of the invention.

This system has the advantage of freedom from noise effects due to the intermediate frequency amplification and the low impedance of the capacity pick-up at its frequency of operation. Shielding against low frequency electromagnetic 40 effects will not be so essential as in low frequency pick-up systems.

The form of the invention illustrated in Fig. 3 depicts the frequency variation method of pick-up in which the conductor 33 from the capacity pick-up plates 28, shown in Fig. 2, is connected to one end of an inductance coil 50 and the conductor 29 from the strings 26 is grounded. The coil 50 forms part of an oscillatory circuit 51 which includes a tube 52 a coil 53, inductively coupled to the coil 50, and a battery 55. Connected between a tap on the coil 50 and ground is a potentiometer 56, the adjustable contact of which is connected to the first grids of two pentode tubes 57 and 58 which are connected in 55 push-pull arrangement.

The output circuits of the two tubes 57 and 58 include two tuned circuits 59 and 60, the former being tuned higher and the latter lower than the mean frequency of the oscillator 51. The tuned 60 circuits 59 and 60 are connected through two condensers 61 and 62 to two rectifiers 65 and 66, the output circuits of which are connected through two filter networks 67 and 68 to two audio amplifiers 69 and 70. The output circuits 65 of the amplifiers 69 and 70 are connected through a transformer 71 to a power amplifier 72 the output circuit of which is connected to a loud-speaker 73.

In the operation of the form of the invention 70 shown in Fig. 3 the oscillatory circuit 51 generates a high frequency voltage across the output potentiometer 56, the frequency of which varies in accordance with the variations in capacity of the pick-up device 26-28, shown in Fig. 2, due 75

to the vibrations of the strings 26 when the piano is played. This frequency modulated signal is impressed upon the tubes 57 and 58 where it is amplified and is fed to the two tuned circuits 5 59 and 60 which are respectively tuned above and below the mean frequency of the oscillator 51.

The tuned circuits 59 and 60 convert the frequency modulated signal to amplitude modulated signals with the modulation for the circuit 59 out 10 of phase with the modulation for the circuit 60. These modulated signals are then detected by the rectifiers 65 and 66 to produce audio frequency currents out of phase. These audio signals are then filtered by the filters 67 and 68 and are impressed upon the input circuits of the audio amplifiers 69 and 70, where they are amplified and pass through the transformer 71 to the power amplifier 72. Here the signals are further amplified 15 and are impressed upon the loud-speaker 73 20 where they are reproduced as musical tones in the usual manner.

In this system the push-pull nature of the demodulators and the audio amplifier minimizes the effects of any amplitude variations of the oscillator which might be caused by stray disturbances.

It is to be understood that the system includes the usual sources of potential and control circuits and that the types of tubes may be varied as desired. Only the essential features have been described herein.

Although only a few of the various forms in which this invention may be embodied have been shown herein, it is to be understood that the invention is not limited to any specific construction but may be embodied in various forms without departing from the spirit of the invention or the scope of the appended claims.

What is claimed is:

40 1. In a musical instrument, a vibratory element, and means for amplifying the sound produced therefrom, comprising a source of super-audible oscillations, a variable reactor, means

varying the impedance of said reactor in accordance with said mechanical vibrations, said reactor being connected to modulate the frequency of said oscillations, a transmission channel including means to demodulate said frequency modulated oscillations to derive audio frequency components therefrom, and means to amplify and convert said components into sound waves. 5

2. In a musical instrument, a vibrating string, a capacity reactance including said string as an element, a source of superaudible oscillations, means modulating the frequency of said oscillations in accordance with variations in capacity of said reactance, a loud speaker adapted to propagate sound waves, a transmission channel including means to demodulate said frequency modulated oscillations to derive audio frequency components therefrom, and means to actuate said loud speaker in accordance with said components. 15

3. The invention set forth in claim 1 in which the transmission channel includes an amplifier for the modulated oscillations adapted to amplify said oscillations prior to demodulation thereof.

4. In a piano, a plurality of vibrating strings, a capacity element mounted adjacent said strings and forming therewith a variable capacity device, a source of super-audible oscillations, a demodulator therefor, means including a bridge circuit for impressing said oscillations upon said demodulator, means including said variable capacity device for varying the transmission characteristics of said bridge circuit so as to modulate said oscillations, said demodulator being adapted to derive audio frequency components from said modulated oscillations and a loud speaker actuated by said components. 25 30 35

5. The invention according to claim 4, in which the bridge circuit is varied in accordance with the energy delivered from the oscillator to the demodulator so as to maintain the necessary unbalance therein for transmission and modulation purposes. 40
